UNITED STATES PATENT OFFICE

109,882

DESIGN FOR A SHOE OR SIMILAR ARTICLE

Mabel Winkel, New York, N. Y.

Application March 29, 1938, Serial No. 76,147

Term of patent 3½ years

To all whom it may concern:

Be it known that I, Mabel Winkel, a citizen of the United States, residing in New York city, in the county of New York, in the State of New York, have invented a new, original, and ornamental Design for a Shoe or similar article, of which the following is a specification, reference being had to the accompanying drawing forming part thereof.

I claim:

The ornamental design for a shoe or similar article, substantially as shown.

MABEL WINKEL
